INTERMITTENT POSITIVE PRESSURE BREATHING MANIFOLD

Harold R. Havstad, Lakewood, and Donald F. Diedrich,
Temecula, Calif., assignors to Hudson Oxygen Therapy
Sales Company

Filed June 22, 1972, Ser. No. 265,336

Term of patent 14 years

Int. Cl. D24—02

U.S. Cl. D83—1 G

FIGURE 1

FIG. 2

FIG. 3

FIG. 4

FIG. 5

FIG. 6

FIG. 7

FIG. 1 is a perspective view of an intermittent positive pressure breathing manifold;

FIG. 2 is a side elevational view of the manifold of FIG. 1;

FIG. 3 is a cross section taken substantially through the center of FIG. 2;

FIG. 4 is a front elevational view thereof;

FIG. 5 is a rear elevational view thereof;

FIG. 6 is a top plan view thereof; and

FIG. 7 is a bottom plan view thereof.

We claim:

The ornamental design for an intermittent positive pressure breathing manifold, as shown and described.
